UNITED STATES PATENT OFFICE.

NIELS ANTON CHRISTENSEN, OF MILWAUKEE, WISCONSIN.

COMPRESSED-AIR STARTER FOR INTERNAL-COMBUSTION ENGINES.

1,230,562.

Specification of Letters Patent. Patented June 19, 1917.

Application filed August 4, 1915. Serial No. 43,565.

To all whom it may concern:

Be it known that I, NIELS A. CHRISTENSEN, a citizen of the United States, residing at Milwaukee, in the county of Milwaukee, and State of Wisconsin, have invented certain new and useful Improvements in Compressed-Air Starters for Internal-Combustion Engines, of which the following is a specification, reference being had to the accompanying drawing, forming a part thereof.

The present invention is designed more particularly for starting multi-cylinder gasoline engines for automobiles of the Ford type.

The main objects of the invention are to avoid the labor and trouble of hand cranking to start engines of this kind; to provide simple, effective and easily installed apparatus for this purpose, the operation of which can be controlled from the dash or other convenient point in the car or automobile by the driver without leaving his seat; and generally to improve the construction and operation of apparatus of this class.

It consists in the construction, arrangement and combination of parts as herein-after particularly described and pointed out in the claims.

30 In the accompanying drawing like characters designate the same parts in the several figures.

Figure 1 is a side elevation showing a starter embodying the invention as applied to a Ford engine; Fig. 2 is a plan view of the same; Fig. 3 is a vertical longitudinal section on the line 3—3, Fig. 2, showing a part of the compressor, the clutch pinion and case and the starter and compressor actuating shaft; Fig. 4 is a vertical longitudinal section on the line 4—4, Fig. 2, showing the compressed air clutch shifter; and Fig. 5 is a vertical cross section on the line 5—5, Fig. 2, showing the starter cylinder, piston and associated parts.

As shown in Figs. 1 and 2, the starter comprises a compressor 1, a compressed air reservoir 2, a starter cylinder 3, and a driver's or controlling valve 4.

50 The compressor, which may be like or similar to that shown and described in my applications for United States Letters Patent Serial No. 630,630, filed June 1, 1911, and Serial No. 805,287, filed December 8, 1913, is closely associated and mounted with the cylinder 3 on a specially designed water

pipe 5, which connects the water jacket of the engine 6, with the radiator (not shown).

The reservoir 2, is mounted on any convenient part of the car or automobile, and is connected by a pipe 7 with the driver's valve 4, which is mounted on the dash or any convenient part of the car within easy reach of the driver.

The valve 4, which is like or similar to the valve shown and described in the above mentioned application Serial No. 630,630, or in my application Serial No. 805,288, filed December 8, 1913, is connected by a pipe 8 with the upper end of the compressor cylinder 1, and by a pipe 9 with the upper end of the starter cylinder 3.

The crank case of the compressor 1 is formed with feet 10, which are bolted to a cross support 11, cast on the water pipe 5.

A pinion case 12, cast in two sections bolted together, as shown in Fig. 3, is formed on opposite sides with extended hubs or bearings 13, for the starter and compressor actuating shaft 14. One of these hubs or bearings may be cast integrally, as shown in Fig. 3, with one of the end covers of the compressor crank case, which is formed or provided with a bearing for one of the journals of the compressor crank 15, a bearing for the other crank journal being formed in the other cover of the crank case in axial alignment with the bearings 13. The pinion case 12 is formed with feet 16, which are bolted to a cross support 17, cast on the water pipe 5, as shown in Fig. 5. For convenience in making the connection with the radiator, the pipe 5 is made in two sections, as shown in Fig. 1, the shorter front section being detachably fastened to the rear section by a bolt 18 passing axially through the longer section and threaded at its front end in the shorter section.

The shaft 14 is provided at its front end, as shown in Figs. 1, 2 and 3, with a sprocket wheel 19, which is connected by a link belt, as indicated in Figs. 1 and 2, with a similar sprocket wheel 20, on the front end of the main crank or engine shaft, so that while the engine is running, the shaft 14 is constantly driven thereby.

Within and inclosed by the case 12, as shown in Figs. 3 and 5, an annular clutch gear or pinion 21 is loosely mounted on a circular clutch head 22, fixed on the shaft 14, the gear being loosely confined in place on the clutch head by washers or cheek

- pieces 23, made in halves and bolted or riveted together through the head. The head 22 is formed in opposite sides of its periphery with tapering recesses in which are loosely confined rollers 24. Spring pressed plinegers 25, inserted in sockets formed in the head 22 and opening into the larger ends of the recesses therein, tend to press the rollers 24 toward the smaller ends of the recesses and to hold the rollers in contact with the inner side of the annular pinion 21. The pinion when rotated by the starter piston in the direction indicated by an arrow in Fig. 5, is thus caused to turn the shaft 14 with it in the same direction, but the shaft when driven by the engine, is permitted to turn independently of the pinion, and the pinion is free to turn thereon in the reverse direction.
- As shown in Fig. 5, the cylinder 3, which for the sake of lightness and strength is preferably made of drawn steel integrally with the upper head, is flanged at its lower end and fastened by screws to a detachable flanged head 26, which in turn is seated upon and bolted to the top of the case 12. The head 26 is formed with a central opening which registers with the upper end of a sleeve 27, which intersects and communicates with the pinion case 12 on one side. A tubular extension 28, is attached to the lower end of the sleeve 27.
- A piston 29, fitted in the cylinder 3, is provided with a downwardly extending tubular rod 30, which is guided in the sleeve 27 and is formed on one side with a rack 31, normally meshing with the pinion 21.
- The piston 29 is provided with a cup leather or other suitable packing 32.
- A spiral retracting spring 33, connected with a hook on a plug 34 in the lower end of the piston rod 30 and passing upwardly therefrom through the piston, is connected at its upper end with a hook on a flanged cover 35 fitting into and closing an opening in the upper end of the cylinder 3 to which it is fastened. This spring holds the piston normally in the upper part of the cylinder 3 a short distance below its upper end with the lower end of the rack 31, in engagement with the pinion 21. A spiral compression spring 36 surrounding the upper end of the spring 33 is seated at its lower end in a counterbore in the upper end of the piston rod 30, and by engagement with the upper end of the cylinder 3, cushions and limits the upward movement of the piston by the spring 33, in the position in which it is shown in Fig. 5, but permits the piston to be forced farther upward by the pinion 21 in case of the back firing of the engine, which sometimes occurs in starting and turns the shaft 14 with the pinion 21 backward. In this event, the lower end of the rack 31 passes out of mesh with the pinion 21 before the piston reaches the upper end of the cylinder, thereby preventing injury to the parts of the starter. The spring 36 under compression, tends to force the piston rod 30 downward with its rack 31, into mesh with the pinion 21, as soon as it is turned to the right in the direction indicated by the arrow, a part of a revolution, until the piston and pinion assume their normal positions, as shown in Fig. 5.
- The arrangement of the retracting spring 33 within the tubular piston rod 30, and its connection with the lower end of the rod and the upper end of the cylinder, as shown and described, admits of the employment of a long spring, and avoids the necessity of unduly lengthening the cylinder and of providing the piston rod with a stuffing box.
- The lower cylinder head 26 is formed as shown in Figs. 1 and 5, with one or more openings, affording free ingress and egress of air below the piston as it moves up and down.
- Adjacent to its front end the longer section of the water circulating pipe 5 is formed with a foot 37, which is bolted to a flange on the crank case of the engine, as shown in Figs. 1 and 5, thereby affording a strong, firm support for the starter, which is mounted thereon as hereinbefore explained.
- The crank 15, which is connected with the compressor piston 38, as shown in Fig. 3, is coupled with or disconnected from the shaft 14 for starting and stopping the compressor, by means of a coupling or clutch member 39, which is rotatable and movable axially in one of the bearings 13 between the rear end of the shaft 14 and the adjacent journal of the crank 15. At its ends this clutch member is formed or provided with tongues fitting corresponding cross slots in the adjacent ends of the shaft 14 and crank journal. One of these tongues is longer than the other, the longer tongue being in constant engagement with the slot in the crank journal while the shorter tongue is movable into and out of engagement with the slot in the shaft 14. The intermediate portion of the clutch member, which is of cylindrical shape, is formed with circumferential teeth meshing with a pinion 40 on a cross shaft rotatably confined and inclosed in a sleeve bearing 41, formed with and transversely to the upper side of the rear bearing 13, which it intersects. Adjacent to its outer end, as shown in Fig. 4, the bearing 41 intersects and communicates with the upper part of a vertical cylinder 42, which may be cast or formed integrally with the main section of the pinion case 12, adjacent crank case cover and intermediate bearing 13. The cylinder 42, which is open at its upper end, is formed with an intermediate centrally perforated partition, and is provided in the lower part with a piston

43, and in the upper part with a cylindrical rack or circumferentially toothed head 44, which is connected with the piston 43 by a rod 45 passing through the intermediate 70
perforated partition of the cylinder and formed or provided with a valve 46 which has a seat in the under side of the partition. The rack or toothed head 44 engages with a pinion 47 on the cross shaft provided with 75
10 the pinion 40, as shown in Fig. 4 and indicated by dotted lines in Fig. 2. The outer end of the cross shaft, which projects from the sleeve bearing 41, is provided, as shown in Figs. 1 and 2, with a cross pin or handle 15 48, for manually turning it and shifting the coupling or clutch member 39 to start or stop the compressor.

For starting and stopping the compressor with compressed air by the manipulation of 20 the driver's valve 4, the lower end of the cylinder 43, which is provided with a removable head, is connected as shown in Figs. 1 and 2, by a pipe 49, with a passage in the head of the compressor cylinder in 25 communication with the pipe 8, the port through which the pipe 8 communicates with the compressor cylinder being provided with an outwardly opening check valve 50.

Automatic lubrication of the several working parts of the starter which require lubrication, is provided for as follows:

An oil supply pipe 51, connected with the upper part of the flywheel case 52 of the engine, as shown in Figs. 1 and 2, leads 35 downwardly therefrom into the rear bearing 13. The pipe 51 is connected with the case 52 by means of a screwthreaded plug or fitting 53, which projects into said case and has an opening in the upper side, as indicated by dotted lines, for catching oil carried up and thrown off by the flywheel, and delivering it to said pipe. The lower end of the tubular extension 28 of the guide and housing for the piston rod 30, is connected, 40 as shown in Figs. 1 and 5, by a pipe 54 with the lower part of the engine crank case 55. The crank case of the compressor is connected below the rear bearing 13, as shown in Fig. 3, by an oil passage 56 with the 45 pinion case 12, which in turn has an overflow opening 57 into the starter piston rod guiding sleeve 27, as shown in Fig. 5.

In the operation of the apparatus, assuming the reservoir 2 to be charged with compressed air at the requisite pressure to start the engine, the driver turns the valve 4 into position to admit air from the reservoir through the pipes 7 and 9 into the upper end of the cylinder 3. The piston 29 is 50 forced quickly downward, and the rack 31 turns the pinion 21 to the right, as indicated by the arrow in Fig. 5, thereby, through the one-way clutch connecting the pinion with the shaft 14, turning said shaft 55 in the same direction, and through the

sprocket wheels 19 and 20, imparting to the engine crank shaft an impulse which causes it to make a number of revolutions. This under ordinary conditions, will be sufficient to start the engine. If, however, the engine fails to start, the operation is repeated. As soon as an explosion takes place and the engine begins to function normally, the shaft 14 will be driven by its connection with the engine crank shaft through the sprocket wheels 19 and 20, the rollers 24 of the one-way clutch slipping back toward the larger ends of the recesses in the clutch head 22 and permitting the pinion 21 to stand still or turn backward.

After the starter piston 29 has been driven downward and has imparted a partial turn to the shaft 14 and a number of turns to the crank shaft of the engine, as above stated, the driver turns the valve 4 back to its normal running position, thereby cutting off communication between the pipes 7 and 9 and establishing communication between the pipe 9 and the atmosphere. The compressed air being thus released from the upper end of the cylinder 3, the retracting spring 33 returns the piston 29 to its initial position, as shown in Fig. 5, the pinion 21 turning freely backward on the clutch head 22. The upward return movement of the piston is arrested before it reaches the upper end of the cylinder, by the compression spring 36, which is stronger than the retracting spring 33 and acts as a yielding stop for the piston.

In case the engine back fires in starting, and turns the shaft 14 backward with the engine shaft, the pinion 21 is permitted to turn therewith without undue strain upon or injury to the parts of the starter, on account of the spring 36, which permits the piston 29 to be forced upward above its normal initial position, till the lower end of the rack 31 passes out of mesh with said pinion, the pinion teeth slipping by the end tooth of the rack. The pressure of the spring 36 however, holding the end tooth of the rack in yielding engagement with the pinion, tends to restore the piston to its initial position and to move the lower end of the rack back into mesh with the pinion teeth when the pinion is again given a partial turn to the right.

To charge the reservoir 2 with compressed air, the driver adjusts the valve 4 to establish communication through the pipes 7 and 8 with the compressor 1, and through the pipe 49 with the lower end of the cylinder 42 of the clutch controller or shifter. Upon the admission of compressed air into the cylinder 42, the piston 43 is driven upward, thereby operating through the rack or toothed head 44 to turn the pinion 47, which operates through the pinion 40 to shift the coupling or clutch member 39 to the left,

as shown in Fig. 3. The shorter tongue of the coupling or clutch member 39 being thus engaged with the slot in the shaft 14 operatively connects said shaft with the crank 15, thereby starting the compressor, which operates to force air through the discharge check valve 50, pipe 8, valve 4 and pipe 7, into the reservoir 2, until the desired pressure is established therein, whereupon the driver returns the valve 4 to its normal position, cutting off the connection between the pipes 7 and 8 and opening the pipe 8 to the atmosphere.

When compressed air is released through the pipes 8 and 49 from the lower end of the controller or clutch shifter cylinder 42, the compressed air confined in the cylinder between the piston and the valve 46, will thereupon expand and force the piston downward, shifting the coupling or clutch member 39 to the right, as seen in Fig. 3, out of engagement with the starter shaft 14, and stopping the compressor. The valve 46, which is seated in the opening in the diaphragm or partition between the upper and lower parts of the cylinder 42 when the piston 43 is forced upward to start the compressor as above explained, prevents the escape of compressed air around the piston rod 45 into the upper part of the cylinder which is open to the atmosphere, and the pressure which accumulates in the cylinder between the valve and the piston is sufficient to force the piston downward when the pressure is released through the pipe 49 from the lower end of the cylinder.

If there is insufficient pressure in the reservoir 2 for starting the compressor, as above explained, by manipulation of the driver's valve 4, the compressor may be started by turning the handle 48 on the shaft of the pinions 40 and 47 to the right, and after pressure has been established in the reservoir and in the controller or clutch shifter cylinder 42, the compressor may be stopped by manipulation of the driver's valve 4, as above explained.

The several parts of the starter requiring lubrication are supplied with oil from the flywheel case 52 through the pipe 51 which leads into the bearing 13 between the compressor and the pinion case 12. From this bearing a part of the surplus oil flows into and collects in the lower part of the crank case of the compressor, from which it overflows through the passage 56 into the lower part of the pinion case 12. From the pinion case 12, surplus oil overflows through the opening 57 into the tubular extension 28 of the piston rod guide bearing 27, and thence through the pipe 54 back into the crank case 55 of the engine. A part of the surplus oil supplied to the rear bearing 13 works around the shaft 14, directly into the pinion case 12. Oil taken up from the lower

part of the case 12 by the pinion 21, is distributed to the parts of the clutch and to the shaft bearings on opposite sides of the case, keeping them thoroughly lubricated. The compressor crank 15 throws the oil collecting in the lower part of the crank case upwardly into the lower end of the compressor cylinder, thereby lubricating the piston 38, some of the oil finding its way into the crank bearings and keeping them lubricated. The rotary coupling or clutch member 39 takes up oil accumulating in the space between the inner end of the shaft 14 and the adjacent crank journal, and carries it to the pinion 40, from which it works through the sleeve bearing 41 to the pinion 47 and the toothed head or rack 44, sufficient oil working downward therefrom around the piston rod 45 into the lower end of the cylinder 42 to keep the piston 43 lubricated.

Various changes in details of construction and arrangement of parts may be made without departure from the principle and scope of the invention as defined in the following claims.

I claim:

1. In a compressed air starter for internal combustion engines, the combination with an engine shaft, of a starter shaft connected therewith, a compressed air reservoir, a cylinder connected with said reservoir, a piston fitting in said cylinder and having a one-way clutch connection with the starter shaft, a compressor having an air connection with the reservoir, a clutch for connecting the compressor with the starter shaft, a compressed air shifter connected with the compressor clutch, and a valve controlling the air connections between the reservoir, starter cylinder, clutch shifter and compressor.

2. In a compressed air starter for internal combustion engines, the combination with an engine shaft, of a starter shaft having a power transmission connection with the engine shaft, a compressed air reservoir, a cylinder connected with said reservoir and provided with a piston having a one-way clutch connection with the starter shaft, a compressor having an air connection with the reservoir, a clutch for connecting the compressor with the starter shaft, a compressed air shifter connected with said clutch, means for manually shifting said clutch, and a valve controlling the air connections between the reservoir, starter cylinder, compressor and clutch shifter.

3. In a compressed air starter for internal combustion engines, the combination with an engine shaft, of a starter shaft having a rotating connection therewith, a cylinder having a compressed air supply connection and a piston provided with a tubular rack rod, a spiral retracting spring passing through the piston into the tubular rod and

- connecting the distant end of the rod with the cylinder on the opposite side of the piston, a compression spring interposed between the piston and the cylinder head on the opposite side of the piston from the piston rod, and a pinion loosely mounted on and having a one-way clutch connection with the starter shaft and normally meshing with the rack rod.
10. 4. In a compressed air starter for internal combustion engines, the combination with the engine shaft, of a starter shaft connected therewith, a compressor, a clutch for connecting the compressor with the starter shaft, a clutch shifter comprising a cylinder, a piston fitted in the cylinder and provided with a rod passing through an opening in one end of the cylinder and connected with the clutch, a valve on the piston rod adapted to close the opening in the end of the cylinder around the piston rod when the piston is moved into position to operatively connect the compressor with the starter shaft, a reservoir connected with the discharge port of the compressor and with the shifter cylinder on the opposite side of the piston from said valve, and a driver's valve adapted to open and close the connection of the reservoir with the compressor and shifter cylinder and to open and close communication between said cylinder and the atmosphere.
5. In combination with an internal combustion engine and a starter therefor, a water circulating pipe provided with means
- for attachment to the engine casing and with supports for the starter.
6. In combination with an internal combustion engine and a starter therefor, a water circulating pipe for the engine composed of two separable sections connected end to end, the longer section having means for attachment to the engine casing and provided with supports for the starter, and a bolt passing axially through the longer section and threaded in the shorter removable section.
7. In a compressed air starter for internal combustion engines the combination with an engine crank shaft, flywheel and case inclosing the same, of a starter shaft connected with the crank shaft, a compressed air motor having a clutch connection with the starter shaft, a compressor having a clutch connection with the starter shaft, the starter shaft and its clutch connections being incased together, and lubricating means comprising an oil conduit leading from the upper part of the engine case adjacent to the flywheel into the casing of the starter shaft and its clutch connections, and an overflow and return conduit leading from said casing into the lower part of the engine case.

In witness whereof I hereto affix my signature in presence of two witnesses.

NIELS ANTON CHRISTENSEN.
